WILLIAM F. THOMPSON AND JOHN LOONEY, OF BIGGS, CALIFORNIA.

COOLING ATTACHMENT FOR EXPLOSIVE-MOTORS.

1,107,728.

Specification of Letters Patent. Patented Aug. 18, 1914.

Application filed July 7, 1913. Serial No. 777,656.

To all whom it may concern:

Be it known that we, WILLIAM F. THOMPSON and JOHN LOONEY, citizens of the United States, residing at Biggs, in the county of Butte, State of California, have invented 5 certain new and useful Improvements in Cooling Attachments for Explosive-Motors; and we do declare the following to be a clear, full, and exact description of the same, such as will enable others skilled in the art to which it appertains to make and use the same, reference being had to the accompanying drawings, and to the characters of reference marked thereon, which form a part 10 of this application.

This invention relates to improvements in explosive motors and particularly to means for keeping the same cool when working hard or running fast, the object of the invention being to produce a cooling attachment whereby by the use of water introduced into the carburetor, the inside cylinders of the motor may be kept cooler than without the attachment. This both saves 20 the wear and tear on the motor and also acts as a big fuel saver and also makes a much lesser consumption of lubricating oil by the motor, and also eliminates about ninety per cent. of the carbon deposits. It 25 also is really a time saver in as much as it is not necessary to stop motors to allow them to cool off after they have been laboring hard as is now usually the case with such motors as are used on tractors or other 30 working devices.

A further object of the invention is to produce a simple and inexpensive device and yet one which will be exceedingly effective for the purposes for which it is designed.

40 These objects, we accomplish by means of such structure and relative arrangement of the parts as will fully appear by a perusal of the following specification and claims.

45 On the drawings, similar characters of reference indicate corresponding parts in the several views.

Figure 1 is an outline view of the explosive motor of a motor vehicle showing our improved cooling attachment thereon. Fig. 2 is a sectional view of our improved cooling attachment. Fig. 3 is a sectional view taken on a line X—X of Fig. 2.

50 Referring now more particularly to the characters of reference on the drawings, the numeral 1 designates the motor, the numeral

2 designates the carburetor, while the numeral 3 designates the intake air pipe of the carburetor.

Our improved cooling means embodies an attachment for the air intake pipe 3 and comprises a means for admitting water to the same by means of the following structure, namely: We first provide a tank or other suitable water receptacle 4 having an outlet pipe 5 provided with a valve 6 at its lower end. This valve 6 projects into the air intake pipe 3 of the carburetor and is provided therein with a discharge nozzle 7. This discharge nozzle 7 discharges into an open pipe or other similar receiving receptacle 8 within the pipe 3, which receptacle 8 has a discharge outlet 9 projecting outside of the pipe 3. The valve 6 has a needle control stem 6^a whereby a desired quantity of water may be admitted to the discharge nozzle 7.

In practice, with the suction of the engine the water will be taken from the receptacle 8 and passed through the carburetor and into the cylinder of the motor where it will thoroughly disseminate among the gases therein and have a tendency to lessen the heat of the explosion and also keep the side walls of the cylinder cooler than if not present. We have also found that in addition to keeping the cylinders cooler, this water causes a lesser consumption of fuel and also, due to the lesser heat it causes the motor to consume a much lesser amount of lubricating oil.

While we have shown in the drawings here presented an auxiliary tank 4 for the water, still if desired the radiating system of the motor may be tapped and the water taken therefrom.

In conjunction with the above cooling means I may use if desired, a heating pipe 10 taken from around the exhaust pipe 11 of the motor and connected with the pipe 3 by means of an intermediate screen member 12 whereby the air may be admitted to the pipes 11 and 3. This screen member 12 is tubular like the pipe and is provided with an outer turnable sleeve 13 whereby the open space may be enlarged or lessened according to the amount of air desired to be taken into the pipe 3.

From the foregoing description it will readily appear that we have produced a cooling means for explosive motors, whereby by

the use of water, the interior of the cylinders may be kept reasonably cool with the attainment of the advantages heretofore noted.

From the foregoing description it will be readily seen that we have produced such a device as substantially fulfills the objects of the invention as set forth herein.

While this specification sets forth in detail the present and preferred construction of the device, still in practice, such deviations from such detail may be resorted to as do not form a departure from the spirit of the invention.

Having thus described our invention what we claim as new and useful and desire to secure by Letters Patent is:—

1. A device of the character described comprising the combination with an explosive motor having an air intake pipe, of a water supply, a pipe leading from said water supply, a valve on the end of such pipe, such valve having a discharge outlet projecting into said air intake pipe, a receptacle disposed within and across said air intake pipe, such receptacle having an open side disposed toward the inlet end of said intake pipe, said discharge outlet on said valve discharging into said open side of said

receptacle, the ends of said receptacle being open and projecting outside of said air intake pipe, as described.

2. A device of the character described comprising the combination with an explosive motor having a carbureter and an exhaust pipe, of an air intake pipe leading from said exhaust pipe and communicating with said carbureter, a screen covered opening in said air intake pipe, a sleeve mounted on said air intake pipe and adapted to form a closure for said opening, a water supply pipe having a valve provided with a discharge nozzle projecting into said air intake pipe between said opening therein and said carbureter, a receptacle within said air intake pipe into which said discharge nozzle empties, said receptacle having open ends projecting outside of said air intake pipe, as described.

In testimony whereof we affix our signatures in presence of two witnesses.

WILLIAM F. THOMPSON.
JOHN LOONEY.
